UNITED STATES PATENT OFFICE.

WILLIAM ALLEN BUTLER, OF SUFFOLK, VIRGINIA.

DESIGN FOR A TRAFFIC-SIGNALING DEVICE.

Application filed August 29, 1928. Serial No. 27,984. Term of patent 14 years.

To all whom it may concern:

Be it known that I, WILLIAM A. BUTLER, a citizen of the United States, residing at Suffolk, in the county of Nansemond and State of Virginia, have invented a new, original, and ornamental Design for Traffic Signaling Devices, of which the following is a specification, reference being had to the accompanying drawing, forming part thereof.

Figure 1 is a face view of a traffic signaling device, showing my new design.

Figure 2 is a side view.

Figure 3 is a plan view.

I claim:

The ornamental design for a traffic signaling device, as shown.

WILLIAM ALLEN BUTLER.
